SPOOL FOR PHOTOGRAPHIC FILMS

Thomas George Baxenden, Watford, and John
Robert Collyear, Bushey, EnglandApplication October 20, 1930, Serial No. 489,959,
and in Great Britain October 30, 1929

3 Claims. (Cl. 242—71)

This invention relates to spools of the type used in film-cameras and more particularly to spools made of sheet metal.

Spools hitherto made of metal consist of a tubular part having diametrically oppositely disposed elongated openings, one of which is equal in length to the width of a film and the other of suitable length to accommodate the tapering end of the red-black paper which covers a film

10 in well known manner.

Such spools are also constructed with end-pieces constituting flanges for the spools, one end-piece having a centrally disposed perforation for the axial stud on which it revolves, and the other 15 end-piece a key-hole consisting of a central opening having diametrically opposite notches, one edge of each of the respective notches having that portion of the metal which remains on one edge after formation of the hole by stamping, bent inwards.

One object of this invention is to provide means for facilitating expeditious insertion of the before-mentioned red-black paper through the opposed openings in instances when, for example, 20 the end of the red-black paper is inclined to curl.

A further object of the invention is to modify the key-hole for a purpose incidental to the improved construction of spool and, further, to provide a stop for the key.

25 According to this invention, the inside of the tubular portion of the spool is provided with spaced walls between the oppositely disposed elongated openings which constitute a guide for the usual red-black paper which covers the film.

30 The respective ends of the guide preferably have an internal configuration conforming to that of the stud on which the spool revolves and of the key-hole and key to constitute a stop for the latter.

35 With this construction insertion of the end of the paper strip covering the film is facilitated as there is no possibility of the end of the paper curling round inside the tubular portion of the spool.

40 Stages in the manufacture of a preferred form of the invention together with alternative constructions are shown in the accompanying drawing, wherein:—

45 Figs. 1, 2 and 3 show stages in the manufacture of one form of spool,

50 Figs. 4 and 5 show cross-sections of alternative constructions of the tubular portion of a spool.

55 Referring first to Fig. 1, which shows the shape of the sheet metal blank from which the tubular portion of the spool is made; the blank 6 is of

substantially rectangular shape and has an elongated opening or slot 7 midway between two of its opposite edges 8, these same edges having portions removed therefrom to constitute a similar slot when the edges are brought together in the manner hereinafter described. The slot 7 and the portions removed from edges 8 are all of the same length and form, in the finished spool, the shorter of the diametrically opposed openings for the end of the paper strip covering the film. The 60 ends of the blank are shaped so as to provide four tongues 9, disposed as shown, for the purpose of attaching the end discs to the tubular portion of the spool as hereinafter described. Two pairs of shallow, rectangular depressions 10, 10¹ are 65 formed in the blank, the lengths of these depressions being approximately equal to the diameter of the tubular portion of the finished spool. The depressions 10 are spaced apart from the depressions 10¹ a distance equal to the length of 70 the longer of the diametrically disposed slots in the spool, and each depression is spaced from the other of the same pair by an amount approximately the same as the width of slot 7.

The blank 6, formed as described with reference to Fig. 1, is bent longitudinally of the slot 7 into U-formation as shown in Fig. 2, so that the portions 10, 10¹ are depressed inwardly and each depression comes adjacent to the other depression of the same pair.

75 At a distance removed from the bend equal to the internal diameter which the spool is to have, that is to say, on a line substantially coincident with the upper ends of depressions 10, 10¹, the two walls of the U-formation are bent 80 outwardly in opposite directions and are then curved inwardly to form the tubular part of the spool, the two edges 8 being brought together so that the opening formed by the cut-away portions of edges 8 coincides with slot 7 and the 85 straight portion 11 of the U-formation constitutes a guide between the oppositely disposed slots for the red-black paper. These oppositely disposed slots are formed by slot 7 and the cut-away portions of the contiguous edges 8 constituting the shorter slot, while the longer slot 12 is formed by the space between the respective 90 pairs of impressed portions 10 and 10¹.

100 When the blank is bent into this position the tongues 9 form an extension of the body of the spool and they are then splayed outwardly in the manner shown in Fig. 3 to form securing means for the end discs 13, only one of which is shown. These discs are of larger diameter than the body of the spool and constitute flanges therefor. The 110

central portion 14 of each disc is recessed and the periphery of the recess 14 is of such formation that it will snap over the upstanding tongues 9 and the end disc 13 be thereby securely held in place, at the same time serving to draw together and retain the meeting edges 8 of the tubular part in tight contiguity. The end disc shown is provided with a key-hole 15 the edges of the straight portion of this key-hole being bent inwardly to form tenons 16 which register with and embrace one end of the guide 11. The other end disc is, of course, merely provided with a central hole to form a bearing for the stud on which the spool revolves.

15 The end portions of the guide 11 may, if necessary, be indented to form an internal configuration corresponding respectively to that of the stud on which the spool revolves, and to the key-hole, thereby forming a stop for the key.

20 In the alternative construction shown in Fig. 4, the tubular part of the spool—formed by stamping and curving the sheet metal into tubular formation—has its edges bent inwardly to constitute parallel inturned flanges 17 of narrow width and which at the ends of the spool, come into contiguity, as at 18, while the part situated between the contiguous portions 18 is separated so as to form the longer slot 12¹. The guide 11¹ comprises a strip of metal which, bent into U-formation is of a width which is nearly equal to the internal diameter of the tubular part and can be slid therein, the inturned flanges 17 passing between the parallel edges of the guide strip and preventing its axial displacement. The guide is provided with a slot 7¹, located at the bend, which registers with a similar slot 19 provided in the tubular portion, these slots forming together the shorter of the guide slots for the end of the paper strip covering the film.

35 In the other alternative form of construction shown in Fig. 5, the inturned flanges 17 extend diametrically and entirely across the tubular part to constitute the guide, their respective edges being located on either side of the shorter slot 19.

40 In both the constructions described with reference to Figs. 4 and 5, the ends of the guide may be formed to conform respectively to the axial

stud and key, and the tubular portion is provided with tongues similar to tongues 9 so that end discs may be fitted in the manner described with reference to the construction first referred to.

80 What we claim as our invention and desire to secure by Letters Patent is:—

1. A photographic film spool, constructed wholly of metal, and comprising a tubular body portion provided with oppositely disposed elongated openings to take the ends of the usual red-black paper which covers the film and end discs attached to said tubular body portion, said body portion having spaced walls extending between the edges of said oppositely disposed elongated openings, portions of said spaced walls near the ends thereof being pressed inwardly to form depressions constituting a stop for the usual winding key.

90 2. A photographic film spool, constructed wholly of metal, and comprising a tubular body portion provided with oppositely disposed elongated openings therein, end discs attached to said body portion, and an internal guide within said body portion, said guide being formed by bending 100 into U-form a blank which is partially slotted on the line of the bend so as to form two substantially parallel surfaces extending diametrically across the interior of the spool between the oppositely disposed elongated openings.

95 3. A photographic film spool, constructed wholly of metal and comprising a rolled-up metal blank forming a tubular member providing oppositely disposed elongated openings therein, end discs attached to said tubular member, and a U- 110 shaped guide within said tubular member, portions of the two walls of the U-shaped member extending outwardly in opposite directions, the free ends of the U-shaped member extending inwardly whereby the free edges of the blank become contiguously, thereby forming the tubular body portion with two substantially parallel surfaces extending diametrically across the interior of the spool between the oppositely disposed elongated openings.
